CLAIM

The ornamental design for a wire holder, as shown and described.

DESCRIPTION

FIG. 1 is an isometric view of a wire holder.

FIG. 2 is an obverse isometric view of the wire holder of FIG. 1.

FIG. 3 is a top plan view of the wire holder of FIG. 1.

FIG. 4 is a bottom plan view of the wire holder of FIG. 1.

FIG. 5 is a front elevation view of the wire holder of FIG. 1.

FIG. 6 is a rear elevation view of the wire holder of FIG. 1.

FIG. 7 is a left side elevation view of the wire holder of FIG. 1.

FIG. 8 is a right side elevation view of the wire holder of FIG. 1.

FIG. 9 is a cross-sectional front elevation view of the wire holder of FIG. 1, taken on the line 9-9 in FIG. 3; and,

FIG. 10 is a cross-sectional left side elevation view of the wire holder of FIG. 1, taken on the line 10-10 in FIG. 3.

Portions of FIGS. 1 through 10 are shown in evenly spaced broken lines illustrating portions of the article that form no part of the claimed design. The dash-dot-dash broken lines in the drawings illustrate the boundary of the claimed design, which forms no part thereof.

1 Claim, 9 Drawing Sheets
